COMBINED SCHOLAR'S COMPANION AND
LOOSE LEAF NOTEBOOK

Elmer Greer, Lego, W. Va.

Application December 30, 1935, Serial No. 56,806

9 Claims. (Cl. 281—31)

My invention relates to school children's supplies and it especially has for its object to provide an improved combination note-book and scholar's companion, of a simple, practical construction, in which there is provided a loose leaf note-book in one of the covers of which is included a box or receptacle, with an outwardly opening lid, the box or receptacle being designed to contain, in orderly fashion, pencils, a pen holder, a ruler, a compass, a protractor, a box for pen points and a box of crayons (or other suitable articles).

A further object of the invention is to provide an improved construction of the character stated in which provision is made for such an engagement between the binder rings and the companion box that when the book is closed twisting of the binder cover, which might tend to tear it loose from the binder back, is prevented.

Other objects will in part be obvious and in part be pointed out hereinafter.

To the attainment of the aforesaid objects and end, the invention still further resides in those novel details of construction, combination and arrangement of parts, all of which will be first fully described in the following detailed description, then be pointed out in the appended claims, reference being had to the accompanying drawings, in which:

Figure 1 is a perspective view of my invention, the lid of the companion box being closed.

Figure 2 is a face view of the same with the lid open.

Figure 3 is a cross section on the line 3—3 on Figure 2 with the lid closed.

Figure 4 is a detail sectional perspective view on an enlarged scale of a portion of the invention.

Figure 5 is a detail sectional perspective showing a side wall of the receptacle cut out to receive a hinge.

Figure 6 is a detail perspective view of the receptacle where it is cut out for a ring of the binder back.

Figure 7 is a detail perspective view of a modified construction.

In the drawings, in which like numerals and letters of reference indicate like parts in all the figures, the binder covers are made of the usual materials, such as a stiffener body 1, 5, enclosed in a facing cover 1a, 5a, and hingedly united to the binder back which likewise is composed of a stiffener member 2 over which a portion 2a of the facing cover is secured. The metallic ring carrier 3 carries the usual rings 4 and may be of any of the well known constructions now acceptable on the market, the construction shown

in the drawings being one in which the rings 4 are pivoted at one side of the carrier 3, as at 4a.

One of the binder covers, say the cover 5, 5a, is provided with an opening through it for access to the scholar's companion box or receptacle now to be described. This box or receptacle comprises a bottom 1, preferably of sheet metal, having outer marginal walls 1c terminating in flanges 1a which abut the inner face of the binder cover 5, 5a, the flanges 1a being bent around the three free sides of the binder cover as at 7b to clamp the same together. The marginal wall 1c which is adjacent the binder back is provided with slots 8 to receive the rings 4 when the book is closed, the rings 4 serving in connection with the slotted portion of the box to prevent twisting of the binder cover on its hinge in its own plane, thus maintaining the binder covers in alignment when the book is closed.

9 designates the lid for closing the opening in the binder cover 5, 5a. The lid 9 is composed of a stiffener enclosed in a cover facing 9a corresponding to that of the binder cover and is also composed of a plate 10 (preferably metal) whose edges are bent over and back as at 11 and 12 to clamp around the edges of the lid member 9, 9a, as best shown in Figures 3 and 4. Portions of the lid are cut away as at 13 for the reception of the hinges 14, one each of whose wings 14a is secured to the lid in any approved manner as by welding or soldering or riveting it to the plate 10. The other wings 14a are suitably secured to the binder cover by rivets 6, or in any other suitable manner (see Figure 4).

The receptacle also in its preferred form, includes an inner marginal wall 15, preferably formed of metal and bent to provide a base portion 16, which is preferably welded or otherwise secured to the bottom of the receptacle. From the base portion of the receptacle there may be a wall 20 extending toward the cover 5, 5a, to cooperate with the strip portion 19 in holding the inner wall member 15 in place. The wall 15 is stepped at 17, 18, to form a rest for the lid (see Figure 4). Portions of the wall 15, 17, 18, 19, 45 are cut away as at 21 to receive the hinges 14 hereinbefore referred to.

22 designates a suitable latch to cooperate with the latch receiving recess 23 in the inner wall for holding the lid closed.

Within the chamber of the box or receptacle and suitably mounted on the bottom 1 are suitable clips 24, 25, 26, 27, to hold the ruler 29, pen holder 30, pencils 31, cylindrical box 35 for containing pens or other articles, protractor 33 and 55

compass 34, respectively. There is also provided a stop 28 to hold a box of crayons 32 in one corner of the receptacle (see Figure 2).

Instead of forming the box or receptacle in the manner hereinbefore described it may be formed as indicated in Figure 7, by reference to which it will be seen that the inner and outer walls 15x, 1cx, base portion 16x, marginal channel portions 1ax, 1bx, for receiving the cover and marginal portion 19x, 18x, 36 and step 17x are formed in one piece, while the bottom of the receptacle proper 1x is preferably simply sheet metal welded or otherwise secured to the base portion 16x, all as clearly indicated in Figure 7 of the drawings.

Other modifications of the structure may be made without departing from the spirit of the invention or the scope of the appended claims.

From the foregoing description, taken in connection with the accompanying drawings, it is thought the construction, uses and advantages of the invention will be clear to those skilled in the art.

What I claim is:

- 25 1. In an article of the character described, a loose leaf binder comprising a binder back, a pair of covers hingedly connected to the back, a binder ring assembly mounted on the inner face of the binder back, a box mounted on the inner face of one of the covers, which cover has an opening through the same, a lid hinged to said cover to close its opening and a latch to hold the lid closed, said box having slots to receive said rings in part.
- 30 2. In an article of the character described, a loose leaf binder comprising a binder back, a pair of covers hingedly connected to the back, a binder ring assembly mounted on the inner face of the binder back, a box mounted on the inner face of one of the covers, which cover has an opening through the same, a lid hinged to said cover to close its opening, a latch to hold the lid closed, said box having slots to receive said rings in part, and means in said box for holding various articles of stationery.
- 35 3. In an article of the character described, a loose leaf binder comprising a binder back, a pair of covers hingedly connected to the back, a binder ring assembly mounted on the inner face of the binder back, a box mounted on the inner face of one of the covers, which cover has an opening through the same, a lid hinged to said cover to close its opening, a latch to hold the lid closed, and means for supporting said box and its carrying binder cover against twisting on the binder back when the binder is closed.
- 40 4. In an article of the character described, a loose leaf binder comprising a binder back, a pair of covers hingedly connected to the back, a binder ring assembly mounted on the inner face of the binder back, a box mounted on the inner face of one of the covers, which cover has an opening through the same, a lid hinged to said cover to close its opening, a latch to hold the lid closed, means for supporting said box and its carrying binder against twisting on the binder back when the binder is closed, said means comprising slots in the box to receive said rings in part.
- 45 5. In a combined note-book and scholar's companion, a binder including a binder back and covers hinged thereto, a leaf-holding-ring assembly mounted on the binder back, one of said covers having an opening, a lid hinged to said cover for closing said opening, a box mounted on the inner face of said cover over its opening, said box comprising a bottom and outer marginal walls, the outer marginal wall which is adjacent the binder back having ring receiving slots into which said rings fit in part when the binder is closed, and said box including an inner marginal wall enclosing an area approximately that of said cover opening.
- 50 6. In a combined note-book and scholar's companion, a binder including a binder back and covers hinged thereto, a leaf-holding-ring assembly mounted on the binder back, one of said covers having an opening, a lid hinged to said cover for closing said opening, a box mounted on the inner face of said cover over its opening, said box comprising a bottom and outer marginal walls, the outer marginal wall which is adjacent the binder back having ring receiving slots into which said rings fit in part when the binder is closed, and suitable scholar's articles-holding elements mounted on the bottom of and within said box.
- 55 7. In a combined note-book and scholar's companion, a binder including a binder back and covers hinged thereto, a leaf-holding-ring assembly mounted on the binder back, one of said covers having an opening, a lid hinged to said cover for closing said opening, a box mounted on the inner face of said cover over its opening, said box comprising a bottom and outer marginal walls, the outer marginal wall which is adjacent the binder back having ring receiving slots into which said rings fit in part when the binder is closed, and suitable scholar's articles-holding elements mounted on the bottom of and within said box.
- 60 8. In a combined note-book and scholar's companion, a binder including a binder back and covers hinged thereto, a leaf-holding-ring assembly mounted on the binder back, one of said covers having an opening, a lid hinged to said cover for closing said opening, a box mounted on the inner face of said cover over its opening, said box comprising a bottom and outer marginal walls, the outer marginal wall which is adjacent the binder back having ring receiving slots into which said rings fit in part when the binder is closed, said box including an inner marginal wall enclosing an area approximately that of said cover opening, and suitable scholar's articles-holding-elements mounted on the bottom of and within said box.
- 65 9. In an article of the character described, a loose leaf binder having a back, rigid covers hingedly connected to the back, one of said covers having an opening, a U-shaped frame mounted on said one cover around the opening thereof and on the inner side thereof, a plate located under said frame as a box bottom, said plate having extensions projected over the margins of the cover to secure the same in place, a binder ring assembly including a mounting plate and rings secured to said back and being of a width approximately that of the back, a lid hinged to said one cover as closure for the opening therein, the depth of said U-shaped frame being approximately one-half the width of the binder back, said plate extending to adjacent the hinged side of the cover and formed to parallel the ring assembly mounting plate and serving by contact with said mounting plate as a stop to limit the closing movement of the cover, said plate having openings to clear the binder rings.
- 70 10. In a combined note-book and scholar's companion, a binder including a binder back and covers hinged thereto, a leaf-holding-ring assembly mounted on the binder back, one of said covers having an opening, a lid hinged to said

cover for closing said opening, a box mounted on the inner face of said cover over its opening, said box comprising a bottom and outer marginal walls, the outer marginal wall which is adjacent the binder back having ring receiving slots into which said rings fit in part when the binder is closed.

10 6. In a combined note-book and scholar's companion, a binder including a binder back and covers hinged thereto, a leaf-holding-ring assembly mounted on the binder back, one of said covers having an opening, a lid hinged to said cover for closing said opening, a box mounted on the inner face of said cover over its opening, said box comprising a bottom and outer marginal walls, the outer marginal wall which is adjacent the binder back having ring receiving slots into which said rings fit in part when the binder is closed, and said box including an inner marginal wall enclosing an area approximately that of said cover opening.

15 7. In a combined note-book and scholar's companion, a binder including a binder back and covers hinged thereto, a leaf-holding-ring assembly mounted on the binder back, one of said covers having an opening, a lid hinged to said cover for closing said opening, a box mounted on the inner face of said cover over its opening, said box comprising a bottom and outer marginal walls, the outer marginal wall which is adjacent the binder back having ring receiving slots into which said rings fit in part when the binder is closed, and suitable scholar's articles-holding elements mounted on the bottom of and within said box.

20 8. In a combined note-book and scholar's companion, a binder including a binder back and covers hinged thereto, a leaf-holding-ring assembly mounted on the binder back, one of said covers having an opening, a lid hinged to said cover for closing said opening, a box mounted on the inner face of said cover over its opening, said box comprising a bottom and outer marginal walls, the outer marginal wall which is adjacent the binder back having ring receiving slots into which said rings fit in part when the binder is closed, said box including an inner marginal wall enclosing an area approximately that of said cover opening, and suitable scholar's articles-holding-elements mounted on the bottom of and within said box.

25 9. In an article of the character described, a loose leaf binder having a back, rigid covers hingedly connected to the back, one of said covers having an opening, a U-shaped frame mounted on said one cover around the opening thereof and on the inner side thereof, a plate located under said frame as a box bottom, said plate having extensions projected over the margins of the cover to secure the same in place, a binder ring assembly including a mounting plate and rings secured to said back and being of a width approximately that of the back, a lid hinged to said one cover as closure for the opening therein, the depth of said U-shaped frame being approximately one-half the width of the binder back, said plate extending to adjacent the hinged side of the cover and formed to parallel the ring assembly mounting plate and serving by contact with said mounting plate as a stop to limit the closing movement of the cover, said plate having openings to clear the binder rings.
